METHOD OF BALANCING STEAM CONSUMPTION IN AIR CONDITIONING

William Warren Cummings, Bradford, Vt.

Application October 29, 1948, Serial No. 57,325

9 Claims. (Cl. 62—176)

1

This invention relates to a method of balancing steam consumption in air conditioning which makes possible savings of 40% or more in operating costs over conventional air-conditioning systems.

Air-conditioning in large commercial installations usually involves controlling both the temperature and the humidity of the air to provide substantially uniform conditions at all times. Air filtering to remove dust and dirt and sterilization are incidental. Complete control of temperature and humidity of course, requires heating the air, as well as cooling it, and adding moisture to the air, as well as extracting it from the air. Heating, however, is normally done separately, and independently of the cooling of the air, and not at the same time.

Air-conditioning as described herein involves both temperature control (by heating or cooling the air) and humidity control (by adding moisture to, or extracting it from the air, as needed). Currently in many large commercial installations, the cooling of the air is done by means of an electrically - driven refrigerating compressor, which supplies refrigerant to pipes over which the air is passed, and the moisture is extracted from the air in an entirely separate process, by chemical sorbents, such as activated alumina, calcium chloride, lithium chloride, silica gel, tri-ethylene-glycol, and the like. The sorbents, however, must be renewed or reactivated from time to time by extracting the moisture from them in turn, which is done by heating the sorbent. Normally, of course, in cooling the air by refrigeration, moisture will be extracted from the air. But this is a haphazard consequence of the cooling, when natural humidity fluctuates widely from time to time, and cannot be used for accurate control of both temperature and humidity without the use of reheat. For instance, to secure a desired humidity, over-cooling of the air may be necessary to remove the required amount of moisture, and then the air will have to be reheated to restore it to its desired temperature. Occasionally, in recent installations, chemical sorbents have been used separately to effect humidity control, but this has necessarily been without relation to temperature control. If temperature and humidity control is sought by use of chemical sorbents alone, the control of either cannot be accurate except in a narrow range since the two conditions bear no normal fixed relationship to each other, but fluctuate widely in nature.

The two processes of temperature and humidity control are therefore, necessarily separate and

2

distinct operations and are usually separately powered, and by different operating media. Occasionally, if the steam plant is available, the refrigerating compressor is driven by a steam turbine, from which the steam is allowed to exhaust, or it may be condensed and fed back to the boiler. I am also aware that this same steam has been used also to reactivate the sorbents. But it has never before been thought possible that the steam requirements for these two separate uses of the steam for refrigeration and reactivation of sorbents could be balanced, because of the great variations and fluctuations between natural temperature and humidity conditions at different periods of the year. I have, however, discovered that by using steam for powering both the cooling and dehumidifying operations (i. e. in the latter operation, for reactivating the sorbent by removing the moisture therefrom, after the sorbent has removed the moisture from the air) the steam requirements for the two operations can be balanced, so that the requirement for low pressure or exhaust steam for removing the moisture from the sorbent is always equal to the requirement for high pressure steam for operating the refrigerating unit. The result of using the same steam for these two purposes in this manner is a great saving in operating costs, of 40% or more, amounting to many thousands of dollars per year in large installations.

Briefly, my invention consists in cooling the air by means of a steam driven refrigerating unit (compressor and condenser), dehumidifying the air by chemical sorbents below the designed relative humidity, reactivating the chemical sorbents to remove the moisture therefrom by the exhaust steam from the refrigerating unit, and automatically spraying moisture into the dehumidified effluent air stream to restore its designed relative humidity, which provides an evaporative cooling action in the air, and further reduces the sensible heat load on the refrigerating unit. In this manner the requirement for low pressure exhaust steam for dehumidifying the air (i. e. reactivating sorbents and removing the moisture therefrom) is always equal to the requirement for high pressure steam for cooling the air (i. e. driving the refrigerating unit), and steam is not wasted, as it otherwise would be. In other words, to maintain this balanced steam condition, the sorbent side is operated at peak capacity at all times up to the limit of the exhaust steam furnished by the steam-driven refrigerating unit. With the sorbent side operated at full capacity, which capacity is greater than required to maintain the designed

humidity, more moisture will be taken out than is required for the designed humidity. The humidistat will then be energized to open sprays in the effluent air stream at the absorber unit, thus adding moisture to the air stream. This added water when evaporated into the air stream results in a conversion of the heat of vaporization to cooling the air stream. This in turn absorbs heat from the area, which reduces the steam requirements for operating the refrigeration unit and further reduces the supply of exhaust steam available for reactivating the sorbent. Less moisture is then removed from the sorbent, and its capacity to absorb moisture in the controlled area is reduced, resulting in a rise in relative humidity in the area. When the humidity rises to the desired degree, the humidistat shuts off the spray of moisture into the effluent air stream from the absorber. With the spray shut off, there is no longer any heat removal from the sorbent side of the system through evaporative cooling action, of the sprayed moisture and the temperature and humidity of the controlled area tends to rise. The entire load of heat removal is then thrown on the refrigerating unit, which requires more steam to operate it, and in turn provides more exhaust steam to reactivate the sorbent to a higher concentration and thus remove more moisture from the air stream, and reduce the relative humidity to the desired level. When the relative humidity again drops below the desired level, the humidistat again opens the spray, thus completing the cycle. Thus, regardless of the change in temperature and humidity requirements, the system will at all times arrive at a steam balance, wherein all the steam exhausted from the refrigeration unit will be fully utilized in the reactivation of the sorbent, no more and no less, thereby accomplishing two integrated uses of the same steam.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation, and it is not intended to limit the invention claimed herein beyond the requirements of the prior art.

In the drawing:

Fig. 1 is a diagram of an installation utilizing my method of air conditioning.

Fig. 2 is a diagram of a modification used when solid, instead of liquid, sorbent is used.

In the drawing a typical installation is shown in which my method of air-conditioning may be used. 10 represents an air inlet for outside air and 11 a similar inlet for recirculated inside air. This air may pass through a screen or filter 12 into the area to be controlled. At this point the air may pass through absorber 13 into which a liquid sorbent is sprayed such as lithium chloride or triethylene glycol, to remove moisture from the air and thus dehumidify it. This dehumidified air then passes into the area to be controlled where it is cooled by being drawn through cooling units 15, by fans 16 which force the air across coils or pipes 17, through which chilled water is circulated. These cooling units are preferably arranged on the ceiling of the controlled area. A steam boiler 20 provides the steam for operating both the cooling and dehydrating systems. For

operating the cooling system steam passes through pipe 21 to steam turbine 22 at proper pressure, i. e. generally 240 to 300 pounds per square inch. The turbine 22 in turn drives the compressor 23 of the refrigerating unit 24 containing a suitable refrigerant such as Freon (dichloro-difluoro-methane) and a part of which is the condenser 25. As these are standard refrigerating units their structure need not be described in detail. The refrigerant is directed to the heat exchanger 26 through suitable coils where it is used to chill water which is the cooling medium, as shown in the diagram. The chilled water is then piped, as through pipes 28 to the cooling units 15 where it is returned through return pipe 29, being caused to circulate therethrough by pump 30. A modulating valve 32 controlled by a thermostat 33 regulates the flow of the chilled water through cooling unit 15. The cooling water for the condenser 25 is passed through pipe 34 to the cooling tower 35 being pumped therethrough by pump 36 and is then circulated through pipe 37 to the absorber 13 and returns through pipes 38 and 39 to the condenser 25. At the same time cooling water is by-passed to the heat exchanger 40 through pipes 41 and returned through pipe 42 to pipe 39.

The dehumidifying system is also operated by the exhaust steam from steam turbine 22 which actuates the cooling system previously described. Low pressure exhaust steam (of 8 to 10 pounds per square inch) after operating steam turbine 22 passes through pipe 44 to the liquid sorbent reactuator 45, where the steam is used to reactivate the sorbent in the reactuator 45 to extract the moisture therefrom and thus restore the sorbent qualities of the sorbent liquid. When the relative humidity of the controlled area reaches a point below the designed relative humidity the humidistat 50 automatically causes atomized water to be sprayed into the dehumidified effluent air stream through atomizer 51 controlled by valve 52, water being supplied thereto from any suitable source through pipe 53. It should be understood that standard humidistats operate within a fixed plus or minus range of a desired setting, and if for instance the desired relative humidity is 50% the humidity of the controlled area would drop to approximately 48% before the humidistat would operate, and thus actuate the valve 52 on the atomizer 51. The addition of this moisture in atomized form to the entering air stream provides an evaporative cooling action on the air itself which reduces its temperature and lessens the load on the cooling system including the refrigerating unit 24 and cooling unit 15 and the steam required to operate the refrigerating unit 24 supplied through the turbine 22.

Again, when the relative humidity rises to the desired degree, the humidistat will shut off the spray of moisture into the air stream. Thus the sorbent side of the system no longer removes heat, and the load on the refrigerating unit increases, requiring more steam to operate it, and thus providing more exhaust steam to reactivate the sorbent.

If solid, instead of liquid, sorbent is used, such as activated alumina, calcium chloride or silica gel, an alternative reactuator for solid sorbent may be provided, as illustrated in the diagrammatic drawings (Fig. 2). This is a modification of my method, to be used when solid, instead of liquid, sorbent is used. Outside air again is introduced through the air inlet 60 and room air inlet 61 through filter 62 to absorber 63 for the

solid sorbent, which again extracts moisture from the air and thus dehumidifies the air. The air in turn passes out into the controlled area through duct 64 being forced therethrough by fan 65. Again an alternate humidistat 70 automatically introduces atomized water into the entering air stream through atomizer 71, valve 72 and water pipe 73. Similarly an alternate thermostat 75 controls the flow of air through the cooling units 15. Again exhaust steam after passing through turbine 22 and thus operating the refrigerator unit 24 and cooling units 15, passes through pipes 44 and 78 to reactivator 80, where sorbent qualities of the solid sorbent are again restored by the use of low pressure steam. The exhaust steam or condensate is then returned to the boiler 20 through pipe 81. The alternate dehumidifying steam using a solid sorbent operates in all respects similar to that of the dehumidifying system using the liquid sorbent previously described. Again as the relative humidity reaches a point lower than the designed relative humidity atomized water is sprayed into the dehumidified air stream through atomizer 71, which again provides an evaporative cooling action in the air and thus reduces the flow on the cooling system and hence the amount of steam supplied to operate steam turbine 22. Regardless, therefore, of the variation between the cooling system and the dehumidifying system, the requirement for low pressure or exhaust steam for removing the moisture from the sorbent, and thus operating the dehumidifying system, is always equal to the requirement for high pressure steam for driving the refrigerating unit, and thus operating the cooling system. It will be understood that in Fig. 2 the dehumidifying chamber for solid sorbent 63 replaces the absorber 13, that temperature and humidity controls 75 and 70 replace equivalent controls 50 and 33, as shown in Fig. 1, when using liquid sorbent, and that the outside air is brought in through inlet 60 instead of 10 (in Fig. 1) and that the room air is brought in through inlet 61, instead of inlet 11 (Fig. 1).

By way of illustration, my method of balancing the steam requirements for cooling and dehumidifying air may be determined in the following manner. The natural state or condition of the air in most climates, of course, fluctuates widely, so far as the relationship between temperature and humidity of the air is concerned, and ordinarily varies from one hour to the next. The purpose of air conditioning, of course, is to keep this relationship at a desired constant, such, for instance, as a temperature of 80° F. and 50% relative humidity. The desired relationship for industrial methods and processes will, of course, vary indefinitely. But with the natural weather conditions varying constantly, it is obvious that under previous methods in use, that the plant requirements for cooling and dehumidifying the air will not normally balance, and that the steam supply would necessarily have to be provided to take care of the maximum or extreme conditions which may be encountered. This necessarily results in high operating costs for plant requirements. Operating costs for refrigeration systems, whether operated electrically or by steam, are approximately the same, and average about 1 1/4 cents per ton hour. The seasonal steam requirements for cooling the air (i. e. sensible heat removal) however, is normally in excess of that required for operating the dehumidifying system (through reactivation of the sorbent). The excess steam, if not usable in industrial processes,

is either exhausted to atmosphere or condensed at additional cost. If the refrigeration system is electrically driven, it is obvious that the steam must be specially generated for reactivating the sorbents of the dehumidifying system. Assuming a total heat problem requiring 100 tons of refrigeration, and using steam of 240 pounds per square inch to drive the steam turbine which operates the refrigerating unit, and a back pressure on the exhaust steam from the turbine of 8 to 10 pounds per square inch, the steam requirements are 2500 pounds of steam per hour, at an operating cost of \$1.25 per hour. This cost is approximately the same as that of an electrically driven turbine, or 1 1/4 cents per ton hour. Assuming a 60-40 proportion for peak loads as normal, the original 100 ton refrigeration load is broken down into 60 tons for the sensible heat load (cooling the air) and 40 tons for the latent heat load (dehumidifying the air.) To obtain a constant steam balance, the equipment is sized for the total heat problem requiring 100 tons of refrigeration, by providing a 60 ton compressor driven by a non-condensing steam turbine—instead of the 100 ton unit which would normally be provided in the conventional and unbalanced system. The remaining 40 tons of the 100 ton refrigerating load is then applied to the dehumidifying system which is sized accordingly. If then the latent heat load of the dehumidifying system is 50% of the designed heat latent load, only 50% of the designed capacity of the absorber is needed to reduce the moisture in the controlled area to the designed relative humidity, reflected by the standard humidistat. When the designed relative humidity is attained, the humidistat automatically operates a valve which sprays atomized water into the dehumidified air stream. In so doing, evaporative cooling occurs in the air, which in turn lessens the sensible heat load on the cooling system. In the examples stated, thus 50% or 20 tons of cooling is accomplished by the dehumidifying system. Thus 60 tons of sensible heat removal is accomplished by the cooling unit, plus 20 tons of sensible heat removal accomplished by the dehumidifying or latent heat removal system. This makes a total of 80 tons of sensible heat removal and a normal 20 tons of latent heat removal, totalling 100 tons of refrigeration, and this is accomplished by the use of steam normally capable of only 60 tons of sensible heat removal in conventional air-conditioning systems.

The sensible heat removal system thus automatically synchronizes with the latent heat removal system, taking only the minimum 240 pounds per square inch steam required to effect a complete condensation. Any decrease in the actual latent heat load over the designed capacity of the dehumidifying equipment increases the capacity of the latter for assuming part of the sensible heat load. This reduces the sensible heat load on the cooling system and it results in a substantial saving in operating costs through a decrease in the pounds of steam required to operate the steam turbine driving the refrigerating system. As an illustration of the actual dollar and cents savings, it has been shown above that the conventional type of air conditioning system can be operated at a cost of \$1.25 per hour per 100 tons of accomplished refrigeration. My system, using 1500 pounds of steam per hour, can be operated for only 75 cents per hour per 100 tons of accomplished refrigeration. In industry installations accomplishing 1000 tons of refrigeration, the savings is approximately \$100,000 per year.

eration per hour are not unusual. The yearly operating costs of conventional air conditioning systems average approximately \$150 per year per ton of refrigeration. For a 1000 ton refrigeration system the savings are at least \$60,000 per year. In addition, remarkably accurate temperature control is possible by my method and control of an area with less than 1 degree F. temperature difference at any one point throughout the area has been commonly experienced.

I claim:

1. The method of air conditioning which combines the cooling and humidification of air in a balanced steam operated dual system utilizing a steam turbine driven refrigerating compressor supplying refrigerant to a cooling element wherein water is cooled, cooling the air by bringing it into heat exchange with the cooled water, removing the moisture from the air by means of chemical sorbents, reactivating the chemical sorbents by utilizing the exhaust steam from the compressor unit and automatically spraying moisture into the dehumidified air until the desired relative humidity has been reached, to provide an evaporative cooling action and to further reduce the sensible heat load on the refrigerating compressor.

2. The method of air conditioning which balances the steam requirements for effecting cooling and humidification of the air in a steam operated dual system including a steam driven refrigerating compressor supplying refrigerant to a cooling element wherein water is cooled, cooling the air by bringing it into heat exchange with the cooled water, removing the moisture from the air by means of chemical sorbents, reactivating the chemical sorbents for dehumidifying the air by utilizing the exhaust steam from the refrigerating compressor unit, and automatically spraying moisture into the dehumidified air until the desired relative humidity has been reached to provide an evaporative cooling action and to further reduce the sensible heat load on the refrigerating compressor.

3. The method of air conditioning which combines the cooling and humidification of air in a balanced steam operated dual system utilizing a steam driven refrigerating compressor supplying refrigerant to a cooling element wherein water is cooled, cooling the air by bringing it into heat exchange with the cooled water, removing the moisture from the air by means of chemical sorbents below the designed relative humidity, reactivating the chemical sorbents by utilizing the exhaust steam from the refrigerating compressor unit, and automatically spraying moisture into the dehumidified air to restore it to its designed relative humidity and to provide an evaporative cooling action and to further reduce the sensible heat load on the refrigerating compressor.

4. The method of air conditioning which balances the steam requirements for effecting cooling and humidification of the air in a steam operated dual system utilizing a steam driven refrigerating compressor supplying refrigerant to a cooling element wherein water is cooled, cooling the air by bringing it into heat exchange with the cooled water, removing the moisture from the air by means of chemical sorbents below the designed relative humidity, reactivating the chemical sorbents for dehumidifying the air by utilizing the exhaust steam from the refrigerating compressor unit, and automatically spraying moisture into the dehumidified air to restore it to

its designed relative humidity and to provide an evaporative cooling action and to further reduce the sensible heat load on the refrigerating compressor.

5. The method of air conditioning which combines the cooling and humidification of air in a balanced dual steam operated system utilizing a steam driven refrigerating compressor supplying refrigerant to a cooling element wherein water is cooled, cooling the air by bringing it into heat exchange with the cooled water, removing moisture from the air in excess of the designed relative humidity by means of a chemical sorbent unit having a designed capacity greater than normally required, reactivating the chemical sorbents by utilizing the exhaust steam from the refrigerating compressor unit, and automatically spraying moisture into the dehumidified air stream to restore it to its desired relative humidity, and thus provide an evaporative cooling action in the controlled area to further reduce the sensible heat load on the refrigerating compressor.

6. The method of air conditioning which combines the cooling and humidification of air in a balanced steam operated dual system utilizing a steam turbine driven refrigerating compressor supplying refrigerant to a cooling element wherein water is cooled, which method includes cooling the air by bringing it into heat exchange with the cooled water, removing moisture from the air in excess of the desired relative humidity by means of a chemical sorbent unit having a designed capacity greater than normally required, reactivating the chemical sorbents by utilizing the exhaust steam from the refrigerating compressor unit, and automatically spraying moisture into the dehumidified air stream to restore it to its desired relative humidity, and thus provide an evaporative cooling action in the controlled area to further reduce the sensible heat load on the refrigerating compressor.

7. The method of air conditioning which combines the cooling and humidification of air in a balanced steam operated dual system utilizing a steam turbine driven refrigerating compressor supplying refrigerant to a cooling element wherein water is cooled, which method includes cooling the air by bringing it into heat exchange with the cooled water, operating at peak capacity a chemical sorbent unit having a designed dehumidifying capacity greater than normally required, removing moisture from the air in excess of the desired relative humidity, reactivating the chemical sorbents by utilizing the exhaust steam from the refrigerating compressor unit, and automatically spraying moisture into the dehumidified air stream to restore it to its desired relative humidity, and thus provide an evaporative cooling action in the controlled area to further reduce the sensible heat load on the refrigerating compressor.

8. The method of air conditioning which combines the cooling and humidification of air in a balanced steam operated dual system utilizing a steam turbine driven refrigerating compressor supplying refrigerant to a cooling element wherein water is cooled, cooling the air by bringing it into heat exchange with the cooled water, removing the moisture from the air by means of chemical sorbents, reactivating the chemical sorbents by utilizing the exhaust steam from the refrigerating compressor unit, and automatically spraying moisture into the dehumidified air whenever the relative humidity of the controlled

area drops below the desired level, to provide an evaporative cooling action in the controlled area.

9. The method of air conditioning which combines the cooling and humidification of air in a balanced steam operated dual system utilizing a steam turbine driven refrigerating compressor supplying refrigerant to a cooling element wherein water is cooled, cooling the air by bringing it into heat exchange with the cooled water, removing moisture from the air in excess of the desired relative humidity by means of chemical sorbents, reactivating the chemical sorbents by utilizing the exhaust steam from the refrigerating compressor unit, and automatically balancing the steam requirements for cooling by resaturating the excessively dehumidified air, whereby the absorbent portion of the steam supply may be converted to sensible heat removal in proportion to the excess of the moisture removal.
